UNITED STATES PATENT OFFICE.

BUEL H. MERRYMAN, OF DEARBORN, MICHIGAN.

CAR CONSTRUCTION.

Application filed May 7, 1923. Serial No. 637,087.

To all whom it may concern:

Be it known that I, BUEL H. MERRYMAN, a citizen of the United States of America, residing at Dearborn, in the county of Wayne and State of Michigan, have invented certain new and useful Improvements in Car Constructions, of which the following is a specification, reference being had therein to the accompanying drawings.

10 This invention relates to railway car construction, and has special reference to the underframing of car bodies, irrespective of the type of trucks supporting the underframing or the construction of the car bodies on the underframing.

In the operation of railways the repair of injured, wrecked or worn cars is an expensive item, mainly because the cars as now constructed must be sent to special shops or stations where the injured parts of the cars can be conveniently repaired or renewed. At times it is necessary to practically disassemble the greater part of the car, in order to reach an injured part thereof and all of this requires considerable time and labor and not only the expense incurred by such time and labor, but the loss by the car being out of service. It is believed that if cars, particularly the underframing thereof, can be fabricated so that all parts of the underframing are accessible, easy to remove and install, that an injured car can be expeditiously repaired, especially if repair parts are plentifully distributed throughout a railroad system to permit an injured car being repaired, at the site of injury or at a shop near by. With this end in view, I have devised a car underframing composed of parts which are more or less standardized and assembled so that the principal parts of the underframing can be readily detached if injured and other parts substituted therefor.

My invention further aims to provide a car underframing wherein the main parts are assembled without the use of rivets or such permanent fastening devices that would prevent connected parts from being easily and quickly disconnected, and such fastening devices as I employ will prevent accidental displacement of any parts of the underframing and at the same time withstand the jars and jolts incident to operation.

55 My invention further aims to provide an underframing for car bodies wherein truck,

and intermediate beams, bumper or end sills, and floor members are assembled relative to a center girder to withstand the stresses and strains to which the underframing is subjected during the use of the same. Associated with these structural elements is a novel sectional floor or platform body with the sections thereof adapted to be removed when access is to be had to certain parts of the underframing, brake rigging, draft appliances, trucks or any other parts in and beneath the underframing.

The above are some of the features of my invention and others will hereinafter appear as the construction of the underframing is described in detail by aid of the drawings, wherein—

Figure 1 is a plan of the car underframing, partly broken away;

Fig. 2 is an enlarged cross sectional view taken on the line II—II of Fig. 1, showing an intermediate bottom;

Fig. 3 is an end view of the underframing showing a bumper or end sill with a coupler or draw bar in cross section;

Fig. 4 is a detail perspective view of a portion of a side sill;

Fig. 5 is a longitudinal sectional view taken on the line V—V of Fig. 1;

Fig. 6 is an enlarged bottom plan of an end portion of the underframing showing a car body bolster and an anchor plate;

Fig. 7 is a perspective view of a detached car body bolster;

Fig. 8 is a perspective view of a draft appliance housing;

Fig. 9 is a similar view of one end of the center girder showing reinforcing members therefor;

Fig. 10 is a similar view of a bumper or end sill;

Fig. 11 is a plan of an underframing, partly broken away, such as constructed for a flat or gondola car;

Fig. 12 is an enlarged cross sectional view taken on the line XIII—XII Fig. 11;

Fig. 13 is an end view of the underframing showing an end or bumper sill;

Fig. 14 is a detail perspective view of parts of a side sill;

Fig. 15 is a similar view of a portion of the side sill, and

Fig. 16 is a cross sectional view taken on the line XVI—XVI of Fig. 6.

Reference will first be had to Figs. 1 to 10 inclusive showing an underframing on

which may be mounted a box or coach body and this underframing includes a center girder, car body bolsters, intermediate beams, side sills, end sills, and end reinforcing webs.

Each car body bolster comprises a platform 1 having narrow ends 2 terminating in rectangular blocks 3 provided with rectangular and oblong pin openings 4 and key slots 5, the latter being disposed substantially at a right angle to the former. Depending from the central portion of the platform 1 are opposed filler blocks 6 and these blocks are connected to the end blocks 3 by transverse wide ribs 7, transverse narrow ribs 8 and lateral ribs 9. At the junction of these ribs are side sockets 10, and the transverse wide ribs 7 are provided with air pipe slots 11.

Each intermediate beam of which there may be many depending upon the length of the underframing comprises an I-section 12 having part of its web portion cut away, as at 13 to reduce the weight of the same, and said I-section has its middle portion of greater depth than its ends to conform somewhat to a truss member. At the outer ends of the I-section 12 there are blocks 14 having transverse pin openings 15 and the middle portion of said I-beam is provided with a substantially rectangular opening 16 with the confronting side walls of said opening provided with flange recesses 17, said recesses being at the top and bottom of said opening with the bottom of said opening normally closed by a longitudinal plate 18 detachably connected to the lower flanges of the I-beam by screw bolts 19 entering enlargements 20 on the vertical web of the I-beam. The plate 18 has an end thereof shaped to form an air pipe bracket 18a. The top of the I-beam has sets of sockets 21 somewhat similar to the sockets 10 of the car body bolster.

The center girder comprises two channel bars 22 approximately throughout the length of the underframing and these channel bars are placed in spaced relation, back to back, so as to form somewhat of a box girder. The channel bars are placed, one at a time, in the openings 16 of the intermediate beam and also between the blocks 6 of the car body bolsters with the lateral flanges of the channel bars 22 extending into the flange recesses 17 of the intermediate beams and on to the upper and lower edges of the filler block 6 of the car body bolster. In this manner the car body bolster and intermediate beams will fit against the outer walls of the channel bars 22 and in order to keep said channel bars in a defined relation spacing members are employed. One of said spacing members is in the form of a horizontally disposed channel bar 23 corresponding in length to the chan-

nel bars 22 and the channel bar 23 is placed between the lower edges of the channel bars 22 and riveted or otherwise connected to the plates 18, so that when said plates are connected to said beams the channel bar 23 is held between the channel bars 22. In addition to this longitudinal spacing member I use collapsible spacing members at the intermediate beam. Each collapsible spacing member comprises a bearing plate 24 connected, as at 25 to floor planks 26 and pivotally connected to each bearing plate are side braces 27 serving somewhat as toggle members, said side braces being articulated with a vertical tie rod 28 extending through the channel bar 23 and held relative thereto by nuts or other fastening means. The side braces 27 can be clamped in engagement with the confronting walls of the channel bars 22, as best shown in Fig. 2, thus holding the upper edges of the channel bars 22 against the intermediate beams.

On the upper edges or lateral flanges of the channel bars 22 are placed longitudinal floor members 29 to which the floor planks 26 are suitably connected, and in addition to the floor members 29 there are longitudinal floor members 30 having the ends thereof seated in the sockets 21 of the intermediate beam and the sockets 10 of the car body bolster. The floor members 30 and 29 cooperate in supporting a plurality of the floor planks 26 and by reference to Fig. 1 it will be noted that the floor of the underframing is in sections that are removable from the car body bolsters and intermediate beams. Besides the weight of the floor sections retaining said floor in place these floor sections at the intermediate beams will be tied to the channel bar 23 by the collapsible spacing member.

Each side sill comprises a channel bar 31 having an outwardly turned bottom flange 32 and an outwardly turned top flange 33, and these channel bars extend throughout the length of the underframing and are of greater length than the center box girder or the inmost floor members. On the top flange 33 of each channel bar is an inverted channel shaped rail 34 provided with a lateral flange 35 and riveted or otherwise fixed to said flange, at the ends of the car body bolsters and intermediate beams, are vertically disposed tie members 36 which are mounted against the inner wall of the channel bar 31 with the lower ends of said tie members outturned under the bottom flange 32 of the channel bar 31. The rail 34 is slotted, as at 38, so that the upper ends of the tie members 36 may protrude above the rail and permit of the side wall of a car body being attached to the underframing. The tie members 36 are formed with side brackets 39 riveted or otherwise attached to the lateral flange 35 of the rail 34.

34. These side brackets are adapted to fit against the end blocks 3 of the car body bolsters and the end blocks 14 of the intermediate beams. In the channel bars 31 and 5 the tie members 36 are openings 40 alining with the pin openings 4 of the bolster blocks 3 and the openings 15 of the intermediate beam blocks 14. In such alining openings are placed pins 41 having slots 10 42 for tapered keys 43, said keys drawing the tie members onto the blocks of the car body bolsters and intermediate beams whereby the ends of said bolsters and beams cannot become displaced relative to the side 15 sills of the underframing. The side sills also find support on the ends of the bolsters and beams by virtue of the flanges 35 resting on the bolster and beam blocks and it is through the medium of the pins 41 that 20 said bolsters and beams may be removed downwardly from between the side sills of the underframing.

Each bumper or end sill is substantially in the form of an angle bar having a vertical flange 44 and a lateral flange 45, said flanges supporting end blocks 46 provided with pin openings 47 and key slots 48. The end blocks 46 are set in from the ends of the vertical flange 44 so that the side sills may 25 abut the flange 44, as best shown in Fig. 6 and be connected to said blocks by pins 49 and keys 50, similar to the pins 41 and the keys 43; the pins 49 extending through openings provided therefor in the ends of the channel 30 bars 31 of the side sills.

At the middle portion of each end sill the vertical flange 44 has a depending portion 51 provided with an opening 52, key slots 53, side ribs 54 and apertured bottom flanges 40 or perches 55. The lateral flange 45 has a thickened portion 56 formed with recesses 57.

Referring again to the center girder, the ends of the channel bars 22 are provided 45 with outer reinforcing members 58 which may be welded or otherwise fixedly secured to the channel bars and the lateral flanges thereof. The reinforcing members 58 are adapted to seat on the apertured flanges or 50 perches 55 and abut the depending portion 51 of the flange 44, said reinforcing members having end flanges 59 provided with key slots 60 to register with the key slots 53; heads 61 to fit in the recesses 57 and brace 55 the thickened portion 56 of the flange 45, and opening 62 to permit of nut equipped bolts 63 connecting the reinforcing members 58 to the flanges or perches 55 of the end sill.

60 In connecting the reinforcing members 58 to the flanges or perches 55, I place a transverse supporting bar 76 on the flanges 55 to partially close the opening 52 and permit of said bar supporting the outer end of the draft appliance housing 67. I use another

bar 78 on top of the draft appliance housing 67 and connect the bar 78 to the flange 44 of the end sill by pins or tongues 77 and keys 79, as best shown in Fig. 16, the pins 77 being integral with the bar 78 and extending through the slots 53 of the end sill and the slots 60 of the reinforcing members 58.

Mounted in each end of the channel bar 23, which forms part of the center girder, 75 are opposed tongue blocks 65 and fitted between these blocks is the dove-tailed or grooved head 66 of a draft appliance housing 67 the bottom of which affords a longitudinally disposed anchor plate 68 extending 80 under the end of the channel bar 23 with said channel bar riveted or otherwise connected to lateral flanges 69 of the tongue blocks 65. The head 66 has a vertical opening 70 to accommodate a king pin 71 by 85 which the end of the end framing may be articulated to a truck (not shown).

The anchor plate 68 has lateral wings 72 provided with upstanding flanges 73 having air pipe slots 74. The wings 72 are therefore somewhat channel shape and are adapted to receive the vertical wide ribs 7 of the car body bolsters with the ends of the channel bars 22 and the filler blocks 6 occupying the space between the inner ends 90 of the flanges 73 and the tongue blocks 65, as best shown in Figs. 6 and 8. The slots 74 of the flanges 73 are adapted to aline with the slots 11 of the ribs 7 to receive and hold an air pipe or line that may extend throughout the length of the underframing.

100 In the draft appliance housing 67 I arrange a draft appliance, which for the purposes of the present invention, may be of a conventional form, but which I have somewhat illustrated in its preferred form, in Fig. 5, as comprising a coupler head 80, a draw bar 81, and abutments 82 and 83, sets of wedge members 84, an interposed 110 spring 85, lateral cross members 86, side spring casings 87 for springs 88 interposed between the ends of the cross members 86, and transverse keys 89. All of these elements cooperate in yieldably holding the draw bar 81 and its coupler head 80 so that said draw bar will be cushioned when shifted in the draft appliance housing 67 incident to the coupling and uncoupling of cars and the relative movement of one car to another during railway operation.

Connected to the lateral flanges 35 at the ends of the side sills are horizontally disposed reinforcing webs 90 provided with stiffening fingers 91 and longitudinal sockets 92 to receive the endmost floor members 80 as best shown in Figs. 1 and 6.

Reference will now be had to Figs. 11 to 15 inclusive showing certain changes which are made in connection with the underframe

- to permit of it being used in connection with a flat bottom car or gondola. The main changes are at the side sills and channel bars 93 are employed with the flanges 94 thereof 5 extending inwardly and the lowermost flanges provided with blocks 95 having pin openings 96. Fitted against the blocks 95 are tie members 97 having flanges 98 extending under the blocks 95 and flanged brackets 99 10 connected to a longitudinal rail 100. In this instance the longitudinal rail 100 is on the inner side of the channel bar 93 instead of on top of the channel bar, as shown in Fig. 4, and the floor planks may rest on the rails 15 100.
- At the outer sides of the channel bars 93 are stake sockets 101 for stakes 102 and said stake sockets are provided with pins 103 extending through the blocks 95, the tie members 97 and the end blocks of the car body bolsters and intermediate beams, the said pins 103 being held in place by keys 104.
- Instead of using the reinforcing webs 90, I may provide the bumper or end sills with 20 sockets 105 to receive the endmost floor members 30.
- While in the drawings, there are illustrated the preferred embodiments of my invention, it is to be understood that the structural elements are susceptible to such changes, in size, shape and manner of assembling, as fall within the scope of the appended claims.
- What I claim is:—
- 35 1. In an under frame construction for cars, car body bolsters, intermediate beams, end sills, side sills connecting said end sills and connected to the ends of said car body bolsters and intermediate beams, a center 40 girder extending through said bolsters and intermediate bolsters and beams and collapsible in said beams for removal purposes, and floor members having ends set in recesses in said car body bolsters and 45 intermediate beams with floor planks attached to said floor members.
2. In an under frame construction for cars, car body bolsters, intermediate beams, end sills, side sills connecting said end sills 50 and connected to the ends of said car body bolsters and intermediate beams, each side sill being composed of a channel bar, a rail on the channel bar and a tie member at the inner side of said channel bar extending upwardly through said rail and having bracket 55 portions under said rail; and a sectpr girder extending through said bolsters and beams and collapsible in said bolsters for removal purposes.
3. An under frame construction for cars 60 including a center girder composed of channel bars, one of said channel bars being mounted between confronting walls of the other channel bars, and collapsible spacing members between the confronting walls of 65 said channel bars adapted to maintain a box-like center girder.
4. An under frame construction for cars comprising beams having blocks at the ends thereof, side sills at the blocks of said beams, 70 pins extending through said side sills into the beam blocks, and keys in the beam blocks and extending through said pins.
5. An under frame construction for cars including a center girder, side sills, a truck 75 beam detachably connected to said side sills and detachably connected to said girder, an end sill, and a draft appliance housing having its ends detachably connected to said girder and to said end sill, the manner of 80 connecting said draft appliance housing and said girder including tongue blocks carried by said girder and a grooved head on said draft appliance housing fitting between said tongue blocks. 85
6. An under frame construction for cars including a girder, a truck beam fitted over said girder, and a draft appliance housing having one end thereof fitted in said girder and connected to said truck beam. 90
7. An under frame construction for cars including beams, side sills attached to the ends of said beams, floor supporting rails forming part of said side sills, and tie members receiving the ends of said sills 95 and extending through said rails.
8. A side sill for a car under frame comprising a channel bar, a floor supporting rail on said channel bar, and a tie member attached to said channel bar and extending 100 through said rail.
9. In a car construction, beams having sockets, floor members having ends thereof in the sockets of said beams, and floor planks connecting sets of floor members to form a floor that may be removed in sections relative to said beams. 105
- In testimony whereof I affix my signature.

BUEL H. MERRYMAN. 116
